LUFTSCHIFFBAU ZEPPELIN GESELLSCHAFT MIT BESCHRÄNKTER HAFTUNG, OF
FRIEDRICHSHAFEN, GERMANY.

SKELETON FRAMEWORK CONSTRUCTION FOR AIRSHIPS AND THE LIKE.

Application filed April 8, 1922. Serial No. 550,886.

To all whom it may concern:

Be it known that I, KARL ARNSTEIN, a citizen of Czechoslovakian Republic, residing at Friedrichshafen a/B., Germany, have 5 invented certain new and useful Improvements in Skeleton Framework Construction for Airships and the like, of which the following is a specification.

My invention has reference to means of 10 constructing skeleton supporting and protecting frames and walls for air ships and the like by means of which great rigidity of the structure with the greatest possible exclusion of deformation of the several elements and of the structure as a whole is 15 obtained, and the mounting and assembling of the several parts into a unit is greatly facilitated.

It is one of the objects of this invention 20 to avoid the drawbacks and inconveniences resulting from lack of uniformity in the distribution of the tension elements heretofore experienced in previous constructions in some of which, for example, each point 25 of juncture of the trusses or rails in skeleton frames of this kind was connected to all the other points of junctures directly by tensional members or the like. Among other objects my invention is particularly intended to provide means to overcome or to 30 counteract the bending strains, and the deflecting tendencies produced by the gas pressure, and in accordance with a preferred form of construction of my invention these 35 tendencies are overcome and the factor of safety of the beams and girders and the like is increased and the free unsupported crackable length thereof is reduced by providing means whereby the tensional struts and 40 stays are so arranged that, instead of extending diagonally through each section constituted by the supporting rings and longitudinal beams or trusses, these tensional members are secured to the two relatively 45 rigid points of juncture at their extremities, and in the thus resulting uniformly tightened condition they are secured by clamping or in a similar manner to the pressure beams, trusses or girders intermediate 50 such junctures. By proceeding in this manner the strengthening elements are prevented from being conducted through the compartments of the air ship or the like, and without being connected to the opposite

points of juncture of the particular section 55 are arranged so as to intersect the longitudinal supporting elements.

Experience has shown that it is impossible to reduce the exposed length of bending resistance of the longitudinal supporting 60 members by transverse tensional members, inasmuch as in structures of this kind 65 in which the tensional wires or the like are originally connected to each individual longitudinal support, and are then tightened, this tightening operation results in a rather unlimited deformation of such longitudinal members, and the bending forces 70 which are thereby brought into play militate against the intended advantage of a reduction of the exposed bending length.

In accordance with my invention these difficulties are overcome by very simple means of construction which are obviously 75 also applicable to other than longitudinal supports of the kind referred to, and in all such cases the tensional wires or strengthening members according to my invention are preferably adapted to serve not only as a means of reducing the free length exposed 80 to bending forces, but also as diagonal struts for the transmission of transverse forces. By proceeding according to my invention the free bending length is reduced 85 without the danger of creating additional bending or deforming forces.

My invention among other uses is particularly applicable for the construction of the skeleton frames of air ships, and for the construction and strengthening of the 90 so-called gangway or tunnel of rigid air ships. A gangway of this kind which heretofore used to be constructed of rigid beams or supports provided with ordinary diagonal tension members, may be provided in accordance with this invention with side walls of girder frame work consisting of pressure-proof diagonal struts, wires or the like, the exposed bending length being reduced 95 by clamping such members to tautly secured wires which extend from one point of juncture to the other. By proceeding in this manner a gangway or tunnel is obtained 100 which is particularly adapted to serve the various functions assigned to it by modern aeronautics in combination with the frame of the air ship proper, and which heretofore were only incompletely accomplished 105

by a large number of rather complicated structures. My invention is of great importance as a means of improving the construction of air ships of very large size in which the large distance of the compartment walls, and of the tightened supporting rings results in a very large exposed free span of the gangway. In the case of tunnels of great height the drawback of increase of load by the large exposed bending length of the pressure-proof diagonal members is overcome by securing the diagonal members by clamping or in a similar manner to wires which are tautly drawn, and intersect the beams, or trusses, which results in this case likewise in a great reduction of the bending length.

The lateral compensation of the stress of the frame work struts in the practical application of my invention may be produced by running wires from a fixed point on the supporting ring to the frame work girder adjacent said ring, the said wires being fastened to said girder, and being then made to intersect the intervening girders or struts to which they are connected by clamping or in a similar manner, and then joining the girder or strut adjacent the next supporting ring, and being finally connected at their other ends to a fixed point on the next supporting ring.

Another means of lateral compensation of the stresses which also serves for the stiffening of the frame work consists in arranging the compensating wires between the ridge supporting beam for the gangway and the lower lateral supporting beams thereof in zigzag fashion and contrary to the direction of the tension of the girders, the wires being preferably joined to the gangway girders by clamping or in a similar manner at the intersecting points. The points on the supporting beams for the gangway at which the tensional members are caused to act, are preferably secured by vertical struts or the like against the pressure of the lower lateral gangway girders or supports. The points on the lower lateral tunnel supports at which the tensional members are caused to act may be sufficiently secured and stiffened by transverse supports connecting the two lateral gangway supports and the central gangway support.

By proceeding in this manner I am enabled to do away with the long suspension members heretofore employed and passing through the compartments of the air ship, and a structure of less weight is thereby obtained which is considerably more rigid than the previous construction, and is more adapted to operate as a kind of pressure girth for the air ship, and at the same time the advantage is obtained that the dangerous perforation of the gas compartments which it is extremely difficult to tighten

against the escape of gas, is avoided. The particular form and construction of the gangway is immaterial; it may be of triangular or rectangular or trapezoid or any other section.

My invention is illustrated by way of example on the accompanying drawing showing skeleton frames and gangways embodying my invention.

Figure 1 is a partial side elevation of an air ship body according to my invention.

Figure 2 is a section through the side of a gangway on the line *a*—*b* of Figure 3.

Figure 3 is a transverse section of a gangway corresponding to Figure 2, and on the line *c*—*d* of the same.

Figure 4 shows a modification of the gangway structure in vertical section.

Figure 5 is another modification of a gangway showing a sectional view through the side wall of the same.

Figure 6 is a section on the line *e*—*f* of Figure 5.

The skeleton frame of the air ship illustrated in Figure 1 in a conventional manner consists of the longitudinal supports *a*¹, *a*², *a*³, etc., the supporting rings *b*¹ and *b*² and the auxiliary rings *c*¹, *c*², *c*³, etc., and of tensional stiffening members. These stiffening members for the sectional fields formed by the longitudinal supports and the rings extend from each point of juncture *p* across substantially the central point of the adjacent longitudinal support intersecting the same, and to another point of juncture *p*. In accordance with my invention the tensional stiffening wires *r* are first secured only at the points of juncture *p*; they are then tightened, and are then secured by a clamping device *x* or the like to the intersecting longitudinal support or girder.

The same means of stiffening and tightening is employed in the gangway structures shown in Figures 2 and 6 of the drawing. In the structure according to Figures 2 and 3 the upper triangular supporting member is designated *g*. With the two lower lateral longitudinal supports *h* it constitutes the frame for the gangway *v*, provided at its bottom with the substantially centrally located running board or support *i*. The side walls are stiffened and secured by scarfs, battens or rods *y*, proof against compressing stress and the exposed binding lengths of which are secured by clamping to the frame work battens or scarfs *h* and by means of two longitudinal wires at the points *z*.

Figure 4 shows a gangway of trapezoid section, but otherwise constructed similar to the one illustrated in Figures 2 and 3. The supporting beam for the gangway is indicated at *g*, the lower lateral supporting member is indicated at *h*, while *i* is the running board or support, and *k* are the struts.

The modification according to Figures 5 and 6 is merely distinguished from the structure shown in Figures 2 to 4 by the use of the wires *m* and of the beams or girders *h*. The wires *m* are arranged in zig-zag fashion between the ridge support *g* and the supporting beams *h* in such a manner as to cause each wire to intersect a strut substantially at the center, being secured thereto at *z* by clamping or in a similar manner. The ridge support *g* at the points of connection of the wires is stiffened against the supporting beams or girders *h* by means of struts *k*.

It is obvious that my invention is capable of a great variety of uses other than those mentioned by way of example in this specification, and I do not intend to be limited to the particular modes of application shown in the drawing which are merely intended as an illustration, but not as a limitation of the invention.

I claim:

1. In a skeleton frame for aircraft and the like in combination, intersecting members in spaced relation to each other and connected at the points of juncture and tensional stiffening members fixed to a point of intersection and extending across one of said intersecting members to another point of intersection, said stiffening members being fixed to said intersecting member also in the crossing point.

2. In a skeleton frame for air craft and the like, a plurality of crosswise arranged frame members in parallel spaced relation to each other and tensional stiffening members connected to the frame members running in one direction, intermediate adjacent points of juncture and angularly extending from said point of connection to the adjacent points of juncture of the frame members running in the other direction.

3. In a skeleton frame for air craft and the like, a plurality of supporting members in parallel spaced relation to each other and running in one direction, a plurality of supporting rings in parallel spaced relation to each other and intersecting said supporting members and connected thereto at the points of intersection, a plurality of intersecting

stiffening tensional members connected substantially at the center of said supporting members intermediate the points of juncture thereof with the rings, and angularly extending from said points of connection to the next adjacent points of juncture of the rings with the longitudinal members.

4. Rigid skeleton frame for air craft comprising in combination, intercrossing supporting members parallelly spaced from each other and connected at the points of juncture, tensional stiffening members angularly extending from a point of juncture to another point of juncture across the intervening adjacent supporting member, and means for fastening said tensional member to the intervening supporting member and to the points of juncture of the intercrossing adjacent supporting members.

5. Rigid skeleton frame for air craft comprising in combination, longitudinal supporting members in parallel spaced relation to each other, a plurality of supporting rings parallelly spaced from each other and crossing said longitudinal members and connected thereto at the points of juncture, a plurality of tensional stiffening members connected to points on each longitudinal supporting member intermediate the points of juncture thereof, and angularly extending in opposite directions from said points of connection and secured to the next adjacent points of juncture of the rings with the longitudinal members, and clamping means for said stiffening means.

6. Rigid skeleton frame for air craft, comprising in combination, a plurality of intercrossing longitudinal and transverse members parallelly spaced from each other and constituting the walls of said structure, stiffening members connected intermediate the points of juncture on the longitudinal members and extending angularly therefrom to the adjacent points of juncture a plurality of angularly extending tensional stiffening wires intersecting the first mentioned stiffening members and means for securing the stiffening members to each other at their points of intersection.

In testimony whereof I affix my signature.

KARL ARNSTEIN. [L. s.]
